UNITED STATES PATENT OFFICE.

ARCHIBALD D. METHVEN, OF MONROE, MICHIGAN.

STRIKE-PLATE.

1,108,873.

Specification of Letters Patent. Patented Aug. 25, 1914.

Application filed November 24, 1913. Serial No. 802,640.

To all whom it may concern:

Be it known that I, ARCHIBALD D. METHVEN, a citizen of the United States of America, residing at Monroe, in the county of Monroe and State of Michigan, have invented certain new and useful Improvements in Strike-Plates, of which the following is a specification, reference being had therein to the accompanying drawings.

10 This invention relates to strike plates and my invention aims to provide a strike plate with a novel latch guide that properly positions a latch, as a door is closed, whereby the latch will enter the latch opening in the 15 strike plate.

My invention further aims to accomplish the above and other results by a simple, durable and inexpensive mechanical construction that can be easily and quickly installed similar to an ordinary strike plate.

20 My invention will be hereinafter specifically described and then claimed, and reference will now be had to the drawing, wherein,

25 Figure 1 is a perspective view of the strike plate; Fig. 2 is a front elevation of the same; Fig. 3 is a rear elevation of the strike plate; Fig. 4 is a perspective view of the improvement in connection with the 30 strike plate of a lock; Fig. 5 is a horizontal sectional view illustrating the strike plate shown in Figs. 1 to 3 inclusive; Fig. 6 is a similar view of the strike plate shown in Fig. 4, and Fig. 7 is a longitudinal sectional 35 view of a modified form of strike plate.

A strike plate in accordance with this invention comprises converging top and bottom walls 1 and 2 connected at their inner edges by a side wall 3. The side wall 3 is of 40 a less length than the walls 1 and 2 and converges, with respect to the outer edges of the walls 1 and 2, to a point in proximity to the inner ends of the walls, thereby providing a vertical shoulder 4, between the inner ends 45 of the walls 1 and 2, adapted to be engaged by a latch 5. The walls 1, 2 and 3 cooperate in providing a tapering channel having a large entrance opening at the outer end on the strike plate.

50 The walls 1 and 2 have the outer edges thereof provided with vertical apertured lugs or ears 6 adapted to receive screws 7 or other fastening means employed for securing the strike plate to the jamb 8 of a door frame. 55 As shown in Fig. 5, the door frame is cut away to provide clearance for the walls 1, 2

and 3, and the inner end of the strike plate extends into a recess 9, which provides clearance for the latch 5 when the door is closed.

The latch guide formed by the walls 1, 2 and 3 is off-set relatively to the lugs 6, and as a door is swung to a closed position, the latch 5 engages the wall 3, and is gradually shifted to a retracted position until the shoulder 4 is reached, when the latch 5 is released and assumes a position behind the shoulder to retain the door in a closed position. Coöperating with the beveled wall 3 are the converging walls 1 and 2 and as the latch rides upon the wall 2, the inclination 70 of said wall is sufficient to raise the free edge of the door and thereby correctly position the door whereby the latch 5 will readily enter the recess 9. A door that has a tendency to sag is therefore correctly positioned 75 in a frame for locking purposes, the latch 5 being supported between the inner ends of the walls 1 and 2 and against the shoulder 4 of the wall 3.

In Figs. 4 and 6 of the drawing a strike 80 plate 10 has a latch opening 11 and lock bolt opening 12. Formed integral with the front edge of the plate 10 is a tapering guide comprising walls 13, 14 and 15, these walls corresponding to the walls 1, 2 and 3 of the strike plate illustrated in Fig. 1. The walls 13, 14 and 15 converge to the forward edge of the latch opening 11 and when said guide is engaged by the latch of a closing door, the latch is gradually retracted by the wall 13 90 until it reaches the forward edge of the opening 11, at which time the latch is released to properly engage in the opening and correctly align the bolt of a lock with the opening 12 of the strike plate. 95

In either form, it will be observed that the strike plate has an off-set tapering guide member with the outer end thereof providing a large entrance opening for a latch and the inner end thereof terminating at a latch opening or recess, which provides clearance for the latch and coöperates with the inner end of the guide member in retaining a door in a closed position. Even though a door is not accurately hung, the guide member 100 springs the door sufficiently for the latch thereof to enter the opening or recess.

From the foregoing it will be observed that I have devised an article of manufacture that can be advantageously used in connection with heavy metallic doors that have 110 a tendency to sag. For instance, in connec-

tion with a cell door the strike plate shown in Fig. 7 can be used, the plate in this instance having a closed-in latch opening or recess 16, which prevents the latch from being tampered with when the cell door is in a closed position. This construction or either of those previously described, can be used to an advantage in connection with automobile bodies.

10 It is a well known fact that in course of time the jarring and vibrations of an automobile body cause the doors thereof to sag and necessitates the lifting of a door before the latch thereof can be properly positioned to engage in a latch opening or recess. By using my improved strike plate the free edge of a door is automatically lifted as it is swung to a closed position, thereby insuring proper alinement of the latch of the door with the latch opening or recess of the door-way.

15 While in the drawings there are illustrated the preferred embodiments of my invention,

it is to be understood that the construction is susceptible to such changes as fall within 25 the scope of the appended claim.

What I claim is:—

A strike plate having bolt and latch openings formed therein, a guide member carried by the front edge thereof adjacent the latch opening and having converging top and bottom walls provided with inclined edges, and a side wall carried by the inclined edge of said top and bottom walls and extending from the forward ends of said top and bottom walls to a point beyond said top and bottom walls and merging into said plate to form a wall of the latch opening and a latch engaging shoulder between said wall.

20 In testimony whereof I affix my signature 30 in presence of two witnesses.

ARCHIBALD D. METHVEN.
